UNITED STATES PATENT OFFICE

116,012

DESIGN FOR A WASHING MACHINE CABINET

Hyman D. Brotman, Detroit, Mich.

Application May 29, 1939, Serial No. 85,243

Term of patent 14 years

To all whom it may concern:

Be it known that I, Hyman D. Brotman, a citizen of the United States, residing at Detroit, in the county of Wayne and State of Michigan, have invented a new, original, and ornamental Design for Washing Machine Cabinets, of which the following is a specification, reference being had to the accompanying drawings, forming part thereof.

Figure 1 is a front elevational view of a washing machine cabinet, showing my new design;

Fig. 2 is a top plan view of the same;

Fig. 3 is a perspective view thereof;

Fig. 4 is a front elevational view on an enlarged scale of the ornamental plate which forms part of the design shown in Figs. 1, 2 and 3;

Fig. 5 a top plan view thereof;
Fig. 6 is a side elevational view of the same;
Fig. 7 a vertical central section on the line 7—7 of Fig. 4;
Fig. 8 a horizontal section on the line 8—8 of Fig. 4;
Fig. 9 a horizontal section on the line 9—9 of Fig. 4, and
Fig. 10 a vertical section on the line 10—10 of Fig. 4.

I claim:

The ornamental design for a washing machine cabinet, as shown.

HYMAN D. BROTMAN.
